(57) **CLAIM**

The ornamental design for an aviation wheel chock as shown and described.

DESCRIPTION

FIG. 1 is an exploded elevated perspective view of a wheel chock according to the present invention;

FIG. 2 is an exploded bottom perspective view thereof;

FIG. 3 is a reverse, top perspective view thereof;

FIG. 4 is a reverse, bottom perspective view thereof;

FIG. 5 is a front view thereof;

FIG. 6 is a rear view thereof;

FIG. 7 is a right side elevation view thereof;

FIG. 8 is a left side elevation view thereof;

FIG. 9 is a top view thereof; and,

FIG. 10 is a bottom view thereof.

The broken lines in the drawings depict environmental subject matter only that form no part of the claimed design. In FIG. 2, the unshaded surfaces between solid and broken lines and the unshaded surfaces within such surfaces illustrate interior portions of the aviation wheel chock that form no part of the claimed design.

1 Claim, 9 Drawing Sheets
